UNITED STATES PATENT OFFICE.

LOUIS L. BENTLEY, OF BEAVER FALLS, AND JOHN W. SLOAN, OF NEW BRIGHTON, PENNSYLVANIA, ASSIGNEES TO ARMSTRONG CORK COMPANY, OF PITTSBURGH, PENNSYLVANIA, A CORPORATION OF PENNSYLVANIA.

SHOE-BOTTOM-FILLING APPARATUS.

Application filed March 12, 1925. Serial No. 14,948.

To all whom it may concern:

Be it known that we, LOUIS L. BENTLEY and JOHN W. SLOAN, both citizens of the United States, residing, respectively, at Beaver Falls and New Brighton, county of Beaver, and State of Pennsylvania, have invented a new and useful Improvement in Shoe-Bottom-Filling Apparatus, of which the following is a full, clear, and exact description.

It is customary in the manufacture of certain types of shoes, particularly the Good-year welt type, to fill the shoe bottom cavity between the innersole and the outer sole with a filler material which is semisolid when cold and capable of application only when heated sufficiently to render it freely plastic or semifluid. This material usually consists of a mixture of comminuted cork, gutta-percha, resin and other materials and is furnished in so-called loaves convenient to handle.

The object of the present invention is to provide an improved apparatus for melting these so-called loaves and applying the semifluid filler material to the shoe bottom cavities. One feature of the invention is the provision of a heating chamber having a grid for supporting the loaves and having a plurality of sheet metal partitions dividing the heating chamber into a number of compartments whereby the heat is more uniformly distributed to all parts of the loaves. Another feature of the invention is the provision of a vent for the steam jacket surrounding the heating chamber whereby the temperature in the heating chamber will be prevented from rising substantially higher than 212° F. Still another feature of the invention is the provision of a revolving paddle in the dip-pot for drawing the melted filler material to the front of the dip-pot, this revolving paddle acting as a sort of closure for the opening in the front wall of the heating chamber, thereby reducing heat losses and facilitating keeping the material in the rear portion of the dip-pot in a semifluid condition.

A preferred embodiment of our invention

is illustrated in the accompanying drawings, in which—

Figures 1 and 2 are respectively a front elevation and a side elevation of the apparatus;

Figure 3 is a plan view of the apparatus with the cover of the heating chamber removed;

Figure 4 is a longitudinal sectional view on the line IV—IV of Figure 3; and

Figure 5 is a transverse section on the line V—V of Figure 4.

Referring to the illustrated embodiment of the invention, 2 designates the dip-pot which is supported by metal legs 3 in the form of angles and connected by suitable braces 4. The dip-pot may be constructed of brick work supported in sheet iron bottom and side plates. The bottom of the filler-receiving cavity 5 of the apparatus is formed by a hot water jacket 6 the walls 70 of which are constructed preferably of sheet copper.

Extending above the rear portion of the dip-pot is the heating chamber 7, the walls 8 of which may be formed of cork. This chamber has a cover 9 of cork board with a sheet iron bottom plate 10. This cover may be hinged at its rear edge as at 11. The cork walls 8 may have an outer facing 12 of sheet iron. A steam jacket 13 surrounds the heating chamber and forms a continuation of the hot water jacket 6. At the bottom of the heating chamber is a grid, consisting of small bars 14, for supporting the loaves of filler material. This chamber is divided into a number of compartments each conveniently of a size to accommodate one loaf, by transverse sheet metal partitions 15, preferably of copper.

Journalized in bearings 16 attached to the front wall of the heating chamber is a rod 17 having a handle 18 at its upper end and having a collar 19 engaging the lower bearing 16. This rod has a paddle 20 mounted on its lower end, the purpose of which will be hereinafter explained.

At one side of the dip-pot is a water filling pipe 21 communicating with the water

jacket 6 whereby the proper amount of water can be supplied to the jacket. At the opposite side of the dip-pot there is a water gauge 22 also communicating with the water jacket whereby the level of the water in the jacket can be observed.

The water in the water jacket can be heated by any suitable means, such as electric resistance elements. The means that we have shown however consists of a steam coil 23 within the water jacket. A steam pipe 24 constitutes a bearing for a roll 25 arranged above the front portion of the cavity 5, this roll being employed to spread and compact the filler material in the shoe bottom cavity and being maintained in a heated condition by the steam which passes through the pipe. The steam is supplied to the pipe 24 by a pipe 26. The pipe 24 passes along the front and one side of the heating chamber, then along the back thereof and communicates with one end of the steam coil at 27. The other end of the steam coil communicates with a steam outlet 28. At one side of the heating chamber is a knife or spatula heater 29 heated by the pipe 24. The supply of steam is controlled by a valve 30. Communicating with the upper portion of the steam jacket 13 is a vent pipe 31.

30 The operation of the apparatus is as follows: The loaves are placed in the heating chamber 7 on top of the grid 14. The steam is turned on and as the water in the water jacket 6 begins to boil, steam rises into the steam jacket 13 and heats the heating chamber. The loaves are slowly melted and the semifluid filler material flows down into the rear portion of the cavity 5. The vent 31 prevents an accumulation of pressure in the steam jacket such as to cause a rise in temperature substantially above 212° F. and hence danger of overheating or burning the filler material is avoided. The paddle 20 in the normal position shown in the drawings forms a partition for the cavity 5, and a sort of closure for the opening between the lower edge of the front wall of the heating chamber and the bottom of the cavity 5. Thus the bulk of the melted filler material is normally maintained in the rear portion of the cavity 5 under the heating chamber. When it is desired to fill the bottom cavity of a shoe, the paddle is revolved to draw some of the melted filler material into the front portion of the cavity 5, whereupon it can be applied to the bottom cavity by means of a spatula.

60 While we have shown and described a preferred form of our invention it will be understood that the invention is not limited to its illustrated embodiment but may be otherwise embodied within the scope of the appended claims.

We claim:

65 1. Shoe filling apparatus comprising a

dip-pot, a heating chamber above the rear portion of the filler-receiving cavity of said pot, means for heating said pot and chamber, and a revolving paddle in said cavity forming in normal position a partition for maintaining the bulk of the melted filler material in the rear portion of said cavity beneath the heating chamber and adapted to be revolved to draw said material into the front portion of said cavity, substantially as described.

2. Shoe filling apparatus comprising a dip-pot, a heating chamber above the rear portion of the filler-receiving cavity of said pot, means for heating said pot and chamber, and a revolving paddle in said cavity forming in normal position a partition for maintaining the bulk of the melted filler material in the rear portion of said cavity beneath the heating chamber and a partial closure for the opening between the lower edge of the front wall of said chamber and the bottom of said cavity, said paddle being adapted to be revolved to draw said material into the front portion of said cavity, substantially as described.

3. Shoe filling apparatus comprising a dip-pot, a heating chamber above the filler receiving cavity of said pot, means for heating said chamber, a grid in the lower end of said chamber for supporting loaves of filler material, and a metal partition in said chamber above said grid adapted to be heated by said heating means, substantially as described.

4. Shoe filling apparatus comprising a dip-pot, a heating chamber above the filler receiving cavity of said pot, a steam jacket surrounding said chamber, a grid in the lower end of said chamber for supporting loaves of filler material, and metal partitions in said chamber above said grid adapted to be heated by said steam jacket, substantially as described.

5. Shoe filling apparatus comprising a dip-pot, a heating chamber above the filler receiving cavity of said pot, a water jacket in the bottom of said cavity, means for heating the water therein, a steam jacket surrounding said heating chamber and communicating with said water jacket, a grid in the lower end of said chamber for supporting loaves of filler material, and metal partitions in said chamber above said grid adapted to be heated by said steam jacket, substantially as described.

6. Shoe filling apparatus comprising a dip-pot, a heating chamber above the rear portion of the filler-receiving cavity of said pot, a water jacket in the bottom of said cavity, means for heating the water therein, a steam jacket surrounding said heating chamber and communicating with said water jacket, a grid in the lower end of said heating chamber for supporting loaves of filler

material, a vertical rod journaled in bearings attached to the front wall of said heating chamber, and a paddle carried by the lower end of said rod and in normal position forming a partition for said cavity for maintaining the bulk of the melted filler material in the rear portion of said cavity,

said paddle being adapted to be revolved to draw the melted material into the front portion of said cavity, substantially as described. ¹⁰
In testimony whereof we have hereunto set our hands.

LOUIS L. BENTLEY.
JOHN W. SLOAN.
